CLAIM

The ornamental design for a telecommunications device, as shown and described.

DESCRIPTION

FIG. 1 is a top front perspective view of a telecommunications device showing our new design;

FIG. 2 is a top rear perspective view thereof;

FIG. 3 is a right side view thereof, the left side being a mirror image;

FIG. 4 is a top view thereof;

FIG. 5 is a front view thereof;

FIG. 6 is a top front perspective view of a second embodiment thereof;

FIG. 7 is a top rear perspective view thereof;

FIG. 8 is a right side view thereof, the left side being a mirror image;

FIG. 9 is a top view thereof; and,

FIG. 10 is a front view thereof.

The broken lines illustrate structure or features that form no part of the claimed design.

The drawings include surface shading that represents contour and not surface ornamentation.
